UNITED STATES PATENT OFFICE.

WILLIAM M. SCOTT, OF PHILADELPHIA, PENNSYLVANIA, ASSIGNOR TO
THE CUTTER ELECTRICAL AND MANUFACTURING COMPANY, OF
NEW JERSEY.

AUTOMATIC MAGNETIC CIRCUIT-BREAKER.

SPECIFICATION forming part of Letters Patent No. 624,895, dated May 9, 1899.

Application filed July 28, 1897. Serial No. 640,167. (No model.)

To all whom it may concern:

Be it known that I, WILLIAM M. SCOTT, a citizen of the United States, residing at Philadelphia, county of Philadelphia, and State of Pennsylvania, have invented a new and useful Automatic Magnetic Circuit-Breaker, of which the following is a specification.

My invention relates to automatic devices that are electrically actuated upon a predetermined condition of flow.

The object of my invention is to produce an electrically-actuated device which shall operate to open the circuit or perform some other required work upon the occurrence or the continuance during a predetermined space of time of predetermined electrical conditions and also certain improvements in circuit-breakers.

In many cases it is desirable to have a circuit-breaker that will not open instantly upon a certain predetermined overflow of current, but will only open upon the continuance of that overflow during a certain space of time and which will instantly open upon a greater predetermined overflow or a short-circuit. I accomplish this by employing in connection with an ordinary type of circuit-breaker means of bringing into circuit upon the occurrence of a predetermined overflow an electrically-actuated device, which I shall hereinafter term a "retarding device," that will require a certain definite space of time to effect the bringing into circuit of the supplemental high-resistance coil, which will immediately actuate its movable core to open the switch. In case the overflow shall have subsided before the supplemental high-resistance coil shall have been brought into circuit the retarding device will be cut out of circuit and its different parts will assume their normal positions.

In the accompanying drawings, Figure 1 is a front view of a specific form of retarding device. Fig. 2 is a side view of same. Fig. 3 is a diagram of the paths of the current. Fig. 4 is a front view of another form of retarding device employing only one coil for the actuation of the core 14. Fig. 5 is a sectional view of the circuit-breaker, showing

the positions of the two coils and the core 50 adapted to be actuated by each.

In Fig. 1, 10 and 12 indicate two solenoid-coils surrounded by magnetic jackets 11 and 13, respectively, the said coils so arranged one above the other that the ends of the movable core 14 are adapted to move in the ends of the two coils, respectively, and to be alternately actuated by each of the said two coils. One end of each coil is connected by the same binding-post, (shown in Fig. 3 at 44,) while 60 the other end of coil 10 is connected with the contact-plate 18, and the other end of the coil 12 is connected through coil 40 of the electromagnet 30 with the contact-plate 17. The switch-arm 16, which is pivoted at 19 and 65 adapted to contact alternately with the contact-plates 17 and 18, is connected through coil 41 of the electromagnet 30 with the other binding-post 45. The switch-arm 16 is provided with shoulders 31 and 32, (shown in Fig. 1,) 70 adapted to engage with the pin 15, which projects from the movable core 14. Until a flow of current through the device the movable core 14 rests in its lowest position, the pin 33, which projects from core 14, rests upon the shoulders 35 of the pivoted arm 22 and prevents the further downward movement of the said core 14. In this condition of my device the current will then pass from one binding-post 75 through coil 41, the switch-arm 16, and the plate 18, with which the switch-arm is in contact, and thence through the coil 10 to the other binding-post. Upon a flow of current through the device the coil 10 is energized to draw the movable core 14 upward into it, carrying the 80 switch-arm 16 with it away from contact with plate 18 and to contact with plate 17, thereby throwing the coil 10 out of circuit and the coil 12 into circuit. The effect of this is to demagnetize the former and magnetize the 85 latter to draw the movable core back to its original position. This operation is repeated during the continuance of a flow of current through the device or until the required movement of the ratchet-bar 26. This ratchet-bar 90 26 is normally supported and guided by the pin 27, which protrudes through the slot 28 in said bar. The bar is further guided by the

slotted post 29 and the armature 42, which is attached to the said bar and adapted to be attracted by the electromagnet 30. The bar 26 is provided with a series of teeth 36, adapted 5 to engage with the pawl 24.

The arm 22 is pivoted at 23 and is provided with shoulders 34 and 35, adapted to engage with the pin 33, which projects from the movable core 14. To this arm 22 is pivoted at 10 25 the pawl 24, adapted to engage upon the upward movement of the arm 22 with the teeth 36 of bar 26 to lift the bar. The coil 40 of the electromagnet 30 is connected in series with coil 12 and plate 17. The other coil 15 41 of said magnet is connected in series with the switch-arm 16 and binding-post 45, so as to be in series with whichever coil is in circuit, as shown in diagram in Fig. 3. Upon the occurrence of a flow of current through 20 the device the coils 10 and 41 are in the circuit, while coils 12 and 40 are out of the circuit. The effect of this is to draw the core upward into the coil 10, as above described, carrying with it the arm 22 and pawl 24, which 25 lifts the bar 26, at the same time the switch-arm 16 is actuated to throw coil 10 out of circuit and coils 12 and 40 into circuit, the effect of which is to energize coil 12 to draw the core back to its original position, and coils 30 40 and 41 both being in circuit the electromagnet 30 is energized to attract the armature 42 and prevent the bar 26 from falling upon being released by the pawl 24. The repeated action of the upward movement of 35 the core is to lift the bar 26 a notch at a time during the continuance of the flow of current through the device until the bar 26 has accomplished the required range of movement to throw coil 58 into circuit to actuate 40 the circuit-breaker to open the main circuit or accomplish any other required work. In case of the abatement or the discontinuance of the flow of current through the device the coil 10 and the electromagnet lose their energy, so that the movable core 14 and the bar 45 26 fall to their original positions, as shown in Fig. 1.

During the continuance of flow of current through the device the operation of the device, while alternately shifting the current from one path to the other, does not materially interfere with the total flow of current.

One side of a portion of the movable core may be flattened, and a suitable piece to engage with said flattened portion of the core may be attached to one of the jackets to prevent the core from turning.

Non-magnetic caps or bushings may be used at the ends of the movable core 14 to prevent 60 it from sticking to the fixed cores 20 and 21.

The set-screw 37 is adapted to engage with the shoulder of pawl 24 as means of its adjustment.

Additional resistance is introduced at 49, 65 Fig. 3, which may be so varied as to render the device applicable to any desired voltage.

While I have described in detail the device

as shown in Figs. 1 and 2 and diagram in Fig. 3, I may modify the same in various ways and still retain the important features already disclosed. For instance, I do not wish to be confined to the arrangement of the coils one above the other adapted to actuate the same movable core. The coils may be side by side, with the movable core of each actuating the 70 same oscillating or pivoted arm, or, as shown in Fig. 4, I may dispense with the coil 12, having a movable core adapted to be actuated in one direction by the coil 10 and in the other direction by gravity. In this case a diagram 75 similar to that of Fig. 3 would show the coil 12 eliminated and the binding-post 44 connected directly to coil 40. The operation of this device is practically the same as that above described, except that upon the movement of the switch-arm 16 away from contact with contact 18, whereby the coil 10 is cut out of the circuit and so demagnetized, the core 14 falls of its own weight or by spring 80 actuation to its original position. A spring 85 may be used also to assure the return of arm 22 upon the fall of the movable core.

A specific form of the circuit-breaker, which is indicated diagrammatically in Fig. 3, is shown in Fig. 5, in which 50 is the usual 90 solenoid-coil, adapted to operate the movable core 51. Attached to the lower end of this core is a circular disk or plate 52, provided with grooves adapted to receive the sides of the frame or stirrup 53 to guide the said movable 100 core. Upon the inner sides of this stirrup are projections 54, adapted to support the washer or plate 55, which surrounds the core 51 and through which the core is free to move. Upon the lower side of this plate 55 and properly insulated therefrom are two contact points or terminals 56 and 57, connected, respectively, one with coil 50 and the other with the binding-post 44, as shown in Fig. 3, the second binding-post 45 being connected with the opposite 110 side of the circuit containing coil 50. The coil 50 is in series with the main circuit and main switch 61. The coil 58, which may be located within coil 50 and adapted also to actuate core 51, is connected between coil 50 115 and contact 59 and is so wound that a relatively small current will energize it to actuate the core 51 to open switch 61 and is of such resistance as to employ only a suitable amount of current upon the bridging of contacts 59 and 60. The contact 60 is connected with the opposite side of the main circuit. Upon a predetermined above-normal flow of current the coil 50 will be energized to draw the movable core 51 upward, causing the plate 120 52 to bridge the contacts 56 and 57 to bring the retarding device into circuit. Upon this condition continuing the bar 26 will be operated to move upward until it bridges the contacts 59 and 60, thereby throwing the coil 58 125 into circuit to energize it to actuate core 51 to operate switch 61 to open the circuit.

In case the abnormal flow should subside before the ratchet-bar 26 shall have reached

the contacts 59 and 60 the movable core 51 will fall away from the contacts 56 and 57 and so cut the retarding device out of circuit. Upon the occurrence of a predetermined greater 5 overflow of current through the coil 50 or a short-circuit the core 51 will be actuated to rise instantly against the weight of the plate 55 to actuate the switch 61 to open the circuit. The operation of the complete device, therefore, is that an abnormal flow not reaching a certain predetermined maximum will only cause the main switch to open upon the continuance of the said overflow during the predetermined space of time required to operate 15 the retarding device to throw coil 58 into circuit; but upon the occurrence of the predetermined maximum flow or a short-circuit the core 51 will be instantly actuated to operate the main switch 61 to open the circuit.

20 In the drawings and above specification I have described a specific form of retarding device which has an oscillating movement and applies that movement to the actuation of a ratchet-bar to close the circuit of the high-resistance coil. It is obvious, however, that other forms of retarding device may be used for this purpose with equal efficiency, and while I believe there is patentable subject-matter in this specific device described by me 25 and have made claims therefor I do not wish in my broad claims to be confined to any specific form of retarding device.

What I claim as my invention, and desire to secure by Letters Patent, is—

35 1. The combination of automatic magnetic means for breaking the circuit upon the occurrence of a predetermined abnormal flow, normally open-circuited automatic magnetic means for breaking the circuit upon the occurrence of a less abnormal flow and automatic magnetic means for bringing into circuit the said normally open-circuited means upon the continuance of said less abnormal flow during a given space of time.

40 2. In an automatic magnetic circuit-breaker the combination of separable coöoperative contacts, two coils, relatively, one of low and the other of high resistance, means adapted to be actuated by each coil to cause the separation 45 of the said contacts, the low-resistance coil normally in circuit and the high-resistance coil normally out of circuit, and means for bringing into circuit the normally open-circuited coil, substantially as described.

55 3. In an automatic magnetic circuit-breaker the combination of fixed and movable contacts, two coils and a core or armature adapted to be actuated by each to cause the actuation of the movable contacts, one coil normally in 60 circuit and one coil normally open-circuited, a retarding device adapted after a predetermined time, during which it is in circuit, to

close the circuit of the normally open-circuited coil and means for bringing into and maintaining in circuit upon and during a predetermined overflow said retarding device. 65

4. In combination with an automatic magnetic circuit-breaker a normally open-circuited coil having a movable core and adapted when brought into circuit to actuate the movable core to effect the opening of the main switch of the circuit-breaker, a retarding device adapted after a predetermined time during which it is in circuit, to close the circuit of the normally open-circuited coil, and means 70 for bringing into circuit upon the occurrence of a predetermined overflow said retarding device and for maintaining the same in circuit during the continuance of said overflow. 75

5. In combination with an electrically-actuated device having an oscillating armature or core, a pivoted arm provided with a pawl pivoted thereto, the said arm adapted to be actuated by the armature or core, a ratchet-bar adapted to engage with the pawl on the 80 pivoted arm and to be lifted by it upon each alternate movement of the pivoted arm and a retaining-magnet adapted to hold the ratchet-bar in its advanced position after the disengagement of the pawl. 90

6. In an automatic magnetic circuit-breaker the combination of stationary and movable contacts, two solenoid-coils, a core movable in each coil, the first coil adapted upon a predetermined overflow of current through it to 95 actuate its movable core to close and maintain closed, during the continuance of said overflow, the circuit of a retarding device, but upon the occurrence of a predetermined greater overflow or short-circuit to actuate said movable core instantly to open the main switch, the second coil normally open-circuited but adapted to be drawn into circuit as hereinafter described, a retarding device normally open-circuited but adapted after a predetermined time during which it is maintained in circuit to close or bring into circuit the normally open-circuited coil to actuate its movable core to open the switch. 100 105

7. In combination with an automatic magnetic circuit-breaker employing a solenoid-coil or electromagnet and a core or armature actuated thereby, a movable piece suitably guided and supported and carrying terminals adapted to be bridged upon the movement of the core or armature and adapted to permit of the full movement of the core or armature only upon the occurrence of a magnetic pull sufficient to overcome the additional restraint imposed by said movable piece. 110 115
